ROY C. PISCITELLO, OF BOONTON, AND DOMINICK N. PISCITELLO, OF JERSEY CITY, NEW JERSEY.

SWEATER.

Application filed August 10, 1925. Serial No. 49,350.

Our invention relates to sweaters or other knitted garments, and the object is to provide a simple and inexpensive attachment adjacent the neck band of the sweater or other garment, consisting of one or more flaps, preferably two in number, which may be either folded within the sweater so that the appearance will be the same as if the flaps were not present, or which may be 10 extended in overlapping position across the chest or throat of the wearer in order to protect the same above the point where the neck band of the sweater proper ordinarily overlaps. We are aware that it is not new 15 to provide garments with flaps for protecting the neck and chest, but it is new to provide flaps of the character herein shown and described. It is not only expensive to make these flaps as separate parts of knitted fabric 20 and to afterwards attach them to the sweater, but the construction is bulky and unsightly. Under the present invention the protective flaps are made as a part of the neck band or facing of a sweater so that 25 these several parts may be formed simultaneously in one operation on an ordinary knitting machine; so that the additional cost of making a sweater with the flaps as against the cost of a plain sweater is merely the 30 actual cost of the additional yarn of which the flaps are constructed. In addition to this, the appearance of the garment having the improved flaps is much neater than where these are separately constructed and 35 afterwards attached to the garment. In addition to forming the flaps with the neck band or facing, we have provided a simple form of construction which permits the flaps to be folded on the lines required and without 40 causing the parts of the garment to pucker or bulge. With these and other objects in view our invention comprises the construction hereinafter described in detail.

In the drawings forming part of this application,

Figure 1 is a front elevation of a garment embodying our invention in which the flaps are shown folded back under the shoulder sections as when not in use,

Figure 2 is a sectional view taken on the line 2—2 of Figure 1,

Figure 3 is a fragmentary view showing the garment broken away from the rear and looking toward the front with the flaps folded within the garment.

Figure 4 is a view corresponding with Figure 1 but with the flaps folded across the chest,

Figure 5 is a sectional view taken on the line 5—5 of Figure 4,

Figure 6 is a perspective view showing the neck band or facing and the flaps for the same as attached to the garment, and

Figure 7 is a sectional view taken on the line 7—7 of Figure 6.

In Figure 1 we have shown a garment such as a sweater, made of knitted fabric, and comprising the body portion 1 and the sleeves 2. There is a collar or facing member 3 which extends from the bottom line 70 of the sweater upwardly, and thence following the contour of the neck, and thence downwardly along the opposite front edge of the garment, being attached in any suitable manner to the body 1 along the line 3. 75 In Figure 1 the flaps 4 and 5 are indicated in dotted lines as being folded back under the shoulder portions of the garment where they are hidden from view, so that the garment has the same external appearance as if the flaps were not present. In this condition it will be understood that the neck band or facing meeting at the point 6 leaves a portion of the neck or chest exposed as in the ordinary sweater. In Figure 2 the flaps 80 are further illustrated as folded within the garment, the same as in Figure 1, and this is also true of Figure 3. In Figure 4 the flaps are shown drawn out and folded across each other to cover that portion of the neck 85 and chest which would otherwise be exposed above the meeting point 6 of the neck band.

In Figure 6 we have illustrated the parts which are formed integrally on the ordinary knitting machine to constitute a neck band 90 or facing as well as the flaps. The end portions 7 of this combined member are the portions represented in the remaining figures

as being attached along the front vertical edges of the body 1 of the garment, which members are usually provided with buttons and buttonholes 8 for attaching the overlapping edges of the garment together. The intermediate portion 9 of the combined member is the portion which is attached to the neck opening along the line 10 of the garment so that this portion forms a loop 10 rounding the neck and has the same general appearance as the ordinary neck band as provided in the standard form of garment. The flaps 4 and 5 shown in Figure 6 are indicated as having the general contour of a rectangle with their opposing ends 11 curved, although the shape of the flaps may be varied without departing from the spirit of our invention. In the preferred form of our invention the flaps are connected along one edge with the edge of the member 3 which is directly attached to the body portion of the garment, by strands of yarn 12 in which the ordinary knitting stitches are omitted, although these strands 20 are continuations of the threads from which the band 3 and the flaps 4, 5 are formed. In forming the band and the flaps the same are made on the ordinary knitting machine, preferably in the form of a continuous tube, as is shown in Figure 7. Starting with the plain tubular portion 7 at one end of the band 3, this tube is formed continuously until a point is reached where the flap 5 occurs, whereupon the knitting operation is 30 extended to increase the width sufficiently to provide, in addition to the band portion, the flap 5. Along one edge of the strip member 3 the yarn is transferred on the needles in well known manner, so that one or more stitches are omitted and this forms the blank or jump threads 12 which are to constitute the connecting or hinge portion between the tubular section 3 of which the band is formed, and the tubular portions of which the flap 5 is formed. When the knitting operation has proceeded to the end of the flap 40 the machine returns to the first operation to continue the formation of the band alone, and this proceeds until the point of the upper edge of the flap 4 is reached, whereupon the operation previously described, regarding the flap 5, are repeated, so that the machine proceeds to form the band portion, and also the flap 4 together with the jump 50 threads connections 12. At the end of the formation of the flap 4 the machine again returns to the formation of the band alone, and this continues to the end of the band; in fact, these operations may continue so that these members are formed in continuous strips of any desired length.

It will be understood that the edges 13 of the flap sections will be closed or finished off by the finishers in the usual manner. It

will be apparent that, as the band and flaps are formed simultaneously and in a continuous piece of knitting, the cost of the same will be no greater than that of knitting the band alone, except for the cost of the additional yarn consumed in making the flaps. It is unnecessary to explain in detail the operation of the knitting machine as it will be apparent to persons skilled in the art the manner of casting off the loops to form the plain jump threads 12.

The combined band and flaps will be attached to the edges of the garment as shown in Figure 1, in the same manner as if the plain band were being attached. In folding the flaps within the garment or moving them out to overlapping position, as shown in Figure 4, the flaps bend or fold in relation to the strip along the lines of the jump threads 12 which act like hinges and permit the flaps to lie in either position without puckering the garment or causing an unsightly bulge. It will be apparent that the cost of attaching the combined strip and flaps is no greater than the cost of attaching the simple band to the body of the garment as in ordinary practice.

We have simplified the construction so that the cost of the flaps is reduced to a minimum, and the appearance of the garment is substantially improved. While we prefer the construction described, in which the band and flaps are of tubular form, we do not wish to be understood as excluding from the scope of our invention similar parts made with a single thickness of material.

Having described our invention, what we claim is:

1. A garment of the class described including a body portion having a front opening and a neck opening, a facing member or band formed of tubular knitted fabric, flaps formed contiguous to one edge of said band, and connected therewith along said edge by jump threads produced by the omission of one or more stitches, said band and flaps being formed integrally, said band being attached along the edge from which said flaps extend, to the front edges of the body, and around the edge of said neck opening, whereby the flaps may be folded within the body portion of the garment or overlapped across the front portion of the neck opening.

2. A garment of the class described including a body portion having a front opening and a neck opening, a facing member or band formed of tubular knitted fabric, flaps of tubular knitted fabric connected to one side edge of said facing member or band by means of jump threads produced by the omission of one or more stitches, said band and flaps being formed integrally, said band being attached along its side edge from which said flaps extend to the front edges

of the body of the garment and around said neck opening.

3. A device for attachment to a garment, including a tubular strip or band of knitted fabric, tubular flaps formed contiguous to and integral with said band by jump threads produced by the omission of one or more stitches in the knitted fabric for connecting

said flaps to said band, said band being adapted to be attached along one edge to the ¹⁰ neck opening of a garment.

Signed at Jersey City, county of Hudson State of New Jersey, this 10th day of June, 1925.
